EARRING

Judith McCann, New York, N. Y.

Application February 20, 1948, Serial No. 9,819

10 Claims. (Cl. 63—14)

1

This invention relates to an earring support and to a combination earring support and ornament. In one aspect, this invention relates to an earring support for holding an ornament adjacent the lobe of a human ear, and which includes a saddle engageable in the concha of the pinna of the ear for carrying the weight of the support and ornament, a body portion overlying an exterior portion of the pinna, and a retainer which is adapted to engage loosely behind the lobe of the pinna to prevent the displacement of the earring from the ear during use.

It is an object of the invention to provide such an earring, in which the support is formed principally of an elongated, or attenuated, piece of material, such as wire, which is deformable at the points where adjustment is necessary, or desirable, to adapt the device to ears of different configurations and so that the retainer can be shaped to fit loosely behind the lobe without exerting pressure thereon.

It is a further object of the invention to provide such an earring support and mounting wherein the support is formed from a continuous length of material, such as wire, one free end thereof being secured to another portion to form a relatively rigid portion of the body.

Another object is to provide such an earring support in which this free end is secured to a contiguous part of the body portion by a pressed-on clamp.

It is still another object to provide such an earring support in which the free end and a contiguous portion of the body are held in engagement by a clamp which is provided with an extended portion or flap for supporting the ornament.

It is another object to provide a novel flap construction in which the flap is formed integrally with a clamp portion, which is secured to the support, and extends therefrom adjacent, but free from, the body of the support and provides positive retention of the ornament in place on the flap.

It is an additional object to provide such an earring in which the support, flap, and ornament are secured together in a novel manner so that the ornament will be anchored securely against displacement during use.

It is a further object to provide such a flap which is particularly adapted for supporting the ornament and which includes a clamp portion integrally formed therewith that is crimped to a free end and a contiguous portion of the body thus making it unnecessary to provide an auxil-

2

iary structure for supporting the decoration and eliminating the necessity for soldering or similar constructional operations.

With these and other objects which will become apparent as the description of the particular embodiments of the invention disclosed in the drawings and described herein progresses, the invention resides in the combination and arrangement of parts disclosed in the drawings, described in the specification, and recited in the claims.

In the drawings which illustrate the best forms in the invention now known to me:

Fig. 1 is an elevational view showing the earring support and ornament securing base in position on a right human ear;

Fig. 2 is an enlarged sectional view taken along line 2—2 of Fig. 1;

Fig. 3 is a sectional view taken along line 3—3 of Fig. 2;

Fig. 4 is a sectional view taken along line 4—4 of Fig. 1;

Fig. 5 is an enlarged sectional view taken along line 5—5 of Fig. 3;

Fig. 6 is an enlarged sectional view taken along line 6—6 of Fig. 3;

Fig. 7 is an enlarged sectional view taken along line 7—7 of Fig. 1;

Fig. 8 is an enlarged perspective view of the earring support;

Fig. 9 is an enlarged perspective view of the decoration supporting flap before being crimped in position on the earring support shown in Fig. 8;

Fig. 10 is a modified form of the decoration supporting flap shown in Fig. 9; and

Fig. 11 is an enlarged sectional view through the ornament supporting flap with an ornament shown in position thereon, the plane of the section being such as is indicated by line 11—11 of Fig. 10.

In order to illustrate best an exemplary construction and application of the earring support, I have shown one form applied to the pinna of a right human ear. It is to be understood that the earring supports are to be provided in pairs adapted to fit the right and left ears, respectively.

For the purpose of describing and illustrating the present invention, I have designated the component parts of the ear as follows: The pinna, or external portion of the ear, is indicated generally by the reference character A; the concha, by the reference character E; the tragus, by the reference character F; the anti-tragus, by the reference character G; the inner wall, or face,

of the tragus, by the reference character K; the inner wall, or face, of the anti-tragus, by the reference character J; the lobe, by the reference character H; and the junction of the lobe, or lower portion of the pinna, and the head, by the reference character I. I have termed the junction of the surfaces of the tragus and the anti-tragus within the concha as inner U of the pinna and designated it by the reference character M, and have termed the junction of the surfaces of the outer portions of the tragus and anti-tragus as the outer U, designated by L.

The inner U usually is depressed at its center, as indicated in the drawing at M, below the point where its faces join the inner face K of the tragus F and the inner face J of the anti-tragus G. The lower portion of the outer U, L, usually is somewhat above the bottom of the inner U, M, and is so indicated in the drawing.

A support 10, shown in Figs. 1 to 8 is formed of elongated or attenuated material which is deformable at those points where adjustment may be desired as described below. Often, in practice, it is more convenient to construct the entire support from deformable material, as for example, from a single length of wire. In order to carry the weight of the earring, the upper end of the support 10 is provided with a saddle 12 (Figs. 1 and 8) which is adapted to fit within the concha of the ear and to seat on the inner faces K and J of the tragus F and anti-tragus G, respectively. This saddle comprises a forwardly extending wing loop 14 and a rearwardly extending wing loop 16, oppositely disposed with respect to the center portion or bight 18 of the saddle 12.

The length of metal, or other material, which forms the saddle 12 extends from the bight 18 of the saddle generally forwardly and upwardly, as at 13, (Fig. 8) and in the opposite direction rearwardly and upwardly, as at 15, is bent back upon itself at each end, as at 17 and 19, and returns to the bight 18 to form the forward and rear loops 14 and 16, respectively.

The effective center line C—L (Figs. 3 and 4) of the saddle, which is curved in the vertical plane and extends lengthwise of the saddle 12, curves upwardly on each side of the center or bight 18 of the saddle 12 and then passes, preferably, through points of inflection near each end of the saddle as the direction of curvature changes.

In order that the loops of the saddle may conform more closely to the shape of the inner faces K and J of the tragus and anti-tragus, respectively, the individual wires of the forward and rear loops 14 and 16 are positioned so that the plane which they define appears to have been twisted or rotated, from the horizontal, for example, about the center line C—L, as shown, respectively, in Figs. 6 and 5. In other words, assuming the support to be in position on a right ear as shown in Fig. 1, and the forward loop to be cut transversely along line 6—6 in Fig. 3, then viewing the receding portions of the wires of the forward loop 14 along the line C—L in the direction of arrow A, the receding wire 20 (Fig. 6) lies forwardly and inwardly of wire 21 and approaches the bight 18 of the saddle at a lesser angle from the horizontal, as shown in Fig. 3. Now assuming the wires which form the rear loop to be cut transversely along line 5—5 in Fig. 3, then viewing the wires 23 and 25 along line C—L, and again in the general direction of arrow A, the wire 23 (Fig. 5) lies inwardly of and slightly above the wire 25 and at substantially the same angle of inclination from the horizontal.

Preferably the longitudinal curvature of the saddle 12 is such that the bight 18 of the saddle bridges the face of the inner U, M, so that it is free therefrom, as shown in Fig. 3. With the longitudinal curvature of the saddle so adjusted and the saddle shaped so that the lower surfaces of the wing loops 14 and 16 of the saddle 12 make contact with the inner face K of the tragus and the inner face J of the anti-tragus, respectively, transverse rocking, as well as rocking of the saddle forwardly and rearwardly, i. e. longitudinally, is prevented. It is to be understood that the exact shape may vary considerably and still provide the advantages pointed out above, such wide variation in primary construction being feasible because of the nature of the material and structure which permit bending of the saddle to alter the transverse configuration of the forward and rear loops 14 and 16 or the longitudinal curvature of the saddle so that the support may be "fitted," by pliers or other means, to the shape which is most comfortable and effective on a particular ear.

The two sections of elongated metal or wire from which the saddle 12 is preferably formed extend outwardly at an angle from the bight of the saddle to form a body portion-saddle bridge 22. This bridge is constructed advantageously so that the two pieces of wire which form the bridge are adjacent to one another as shown in Fig. 8.

These two sections of wire are bent generally downwardly at the outermost portion of the bridge 22 to form body portion 24. One of these pieces of wire extends downwardly a short distance, forms rearwardly extending U shaped loop 26, for the purpose of providing adjustability as described below, and continues thence downwardly over the outer face of the pinna A. The other section of wire extends downwardly, adjacent to the first section, to its free end, which may be, for example, just above the loop 26, as at 28 (Fig. 8).

The wire, or other material, which forms the body portion 24 continues downwardly from the loop 26 and curves inwardly around the lobe H, forming a body portion-retainer bridge 32, and thence generally upwardly and rearwardly at the junction I between the pinna and the head, to form the retainer 34.

Preferably, in use, the distance between point 45 (Fig. 8) and the lowermost point on the body portion-retainer bridge 32 is less than the distance between the top portion of the outer U, L, and the lowermost portion of lobe H, and is, preferably, slightly greater than the distance between the lowermost portion of the outer U, L, and the junction I, and is preferably less than the distance between the junction I and the top portion of the outer U. This relationship, of course, depends upon the configuration of the particular ear with which the device is used.

The retainer 34 fits loosely behind the lobe of the ear so that it does not apply a clamping action thereto but provides an interlocking structure which prevents the lowermost portion of the support 10 from swinging outwardly away from the head, which would cause the support to become disengaged from the ear. The retainer 34 extending rearwardly behind the ear is not intended to contact the back of the ear but to be in close proximity thereto so that if the head of the wearer is moved so that the pinna of the ear faces downwardly, the body portion-retainer bridge 32 of the support and the retainer 34 will engage at the bottom and behind the lobe of the

ear and prevent the bottom of the earring from swinging outwardly. Thus, the earring support is maintained in position by an interlocking action and not by clamping or pressure exerting structures.

Describing the support, when the wings are bent to conform to the particular ear illustrated in the drawing, the single length of wire forming the support 10 may be traced along its length as follows: starting at end 28 (Fig. 8) the wire extends upwardly to the point 46, forming part of the body portion 24, makes an angular turn extending thence a short distance to form one section of the body portion-saddle bridge 22. This wire then makes an angular turn extending generally forwardly and upwardly thence around a generally U-shaped bend and returning, at a lesser angle from the horizontal, to the bight 18 of the saddle 12 to form the forward wing loop 14. The wire continues from this point generally backwardly and upwardly through a second generally U-shaped bend and returns downwardly and forwardly to the bight 18 of the saddle 12 to form the rear wing loop 16. The wire then makes an angular turn and extends, immediately adjacent the section of the body portion-saddle bridge 22 and body portion 24 previously described, to a point adjacent end 28. This portion of the wire support continues downwardly, forms the rearwardly extending adjustment loop 26, and thence downwardly to form the remainder of body portion 24. The wire then curves gradually inwardly, upwardly and rearwardly forming the body portion-retainer bridge 32 and the retainer 34.

It is, of course, to be understood that the wings as well as the other portions of the support may be bent to conform to ears of various configurations.

In order to reinforce the wire support 10 and secure the end of the wire to the body portion 24 and at the same time provide a convenient means for securing to the support a suitable ornament, for example, as illustrated at 36 in Fig. 11, a flap generally indicated at 38 (Figs. 1, 9, 10, 11) is provided. The flap 38 includes a clamp portion 42 which substantially surrounds a short length of wire adjacent the free end 28 and a contiguous portion of the body and is securely fastened thereto, preferably by crimping, so that the structure is maintained in position by a clamping action, eliminating the need for soldering or other difficult and expensive mechanical operations. This clamp 42, which as stated above secures one of the free ends of the length of wire from which the support 10 is formed to the contiguous portion of the body, provides a rigid reinforced body section so that the support will maintain the desired configuration and so that it may be more readily adjusted by bending, with the bending action occurring most readily at the points best suited to producing the desired changes in configuration.

Advantageously, the flap 38 includes an ornament securing extension 44 which is formed integrally with the clamp portion 42 and extends downwardly and rearwardly therefrom adjacent, but free from, the loop 26. It is to be understood that the clamp portion 42 may be constructed without the ornament securing extension, the earring decoration being secured directly to the wire support or to a separate base on the loop 26. However, obvious advantages and economies result from use of a combination clamping and ornament securing flap.

The ornament securing extension 44 of the flap 42 extends over the loop 26 and is free therefrom in order that the full deformability of the loop may be utilized for adjustment purposes. Thus, if it is desired to change the vertical length of the body portion, i. e. the distance between point 46 (Fig. 8) and the body portion-retainer bridge 32, to alter the overall length of the support in accordance with the vertical distance between the outer U, L, and the junction I of the particular ear on which the earring is to be worn, the configuration of the loop 26 may be changed without interference by the ornament securing extension 44 and without danger of causing the decorative portion of the earring to be disengaged accidentally from the support. Thus the support may be readily adjusted, by shortening or lengthening, to adapt it to ears of different dimensions and so that nevertheless the distance between point 46 and the body portion-retainer bridge will be less than the distance from the outer U, L, to the lowermost portion of the lobe H. In addition, the configuration of the body portion-retainer bridge 32, the retainer 34, and the longitudinal and transverse configuration of loops 14 and 16 may be altered, by bending, to accommodate the support to the particular ear on which the earring is to be worn.

The flap 38 may be provided with the ornament securing extension 44 having a flat smooth surface, as shown in Fig. 1, to which a suitable ornament may be secured, for example, by welding, soldering or cementing. Additionally, the ornament securing extension 44A is shown in Fig. 9 provided with a transverse opening, as at 52, in order to permit attachment of ornaments by riveting or staking.

It is often more convenient however, to secure the ornament to the flap by cementing, as for example, with quick drying lacquer type materials. When the extension 44 is provided with a flat smooth surface as in Fig. 1 the adherence of the ornament depends primarily on the surface adhesion between the extension and the cement. I have provided for an abraded or undercut surface whereby the cement when hardened will anchor the ornament 36 securely to the extension 44. For example, the extension 44A (Fig. 9, and 44B in Figs. 10 and 11) may be provided with several inwardly extending cavities or openings 54, for example, such as would be formed by a pointed or wedge shaped tool, and which preferably have at least one surface which forms an acute angle relative to the surface of the extension 44A. Thus, when the ornament 36 is secured to the extension 44B, as shown in Fig. 11, by cement 56, the cement penetrates these openings and when hardened produces an anchoring effect so that the surface adhesion of the cement is effectively increased and the ornament will be anchored in place so that it cannot be dislodged except by a force sufficiently large to overcome the self-tenacity or internal cohesion of the cement, which is higher ordinarily than the surface adhesion between the extension 44 and the cement 56.

In order to facilitate, further, the securing of ornamental decorations to the support, the extension 44B, (Figs. 10 and 11) may be provided with a concave or cup-shaped portion 58. This shape is sometimes better fitted to the configuration of the ornament and provides an inherently more rigid structure. The cup 58 may be provided optionally with the anchoring openings 54 and/or the transverse opening 52. In Fig. 11 the

ornament 36 is shown with its convex surface secured to the concave face of the cup 58 by the cement 56 which has filled openings 54 and, in addition, by a rivet or pin 62 which extends through the hole 52 into the ornament.

It will be observed that the earring support and mounting described herein provides a simplified structure and reduces the complexity of the manufacturing processes, for example, by eliminating all soldering or welding operations and, in addition, provides reinforcement of the support by the ornament securing flap. It is to be further observed that although the flap serves to reinforce the support it does not in any manner interfere with the adjustability of the support and is constructed so that a wide variety of ornamental decorations may be secured thereto conveniently and rapidly.

The term deformable, used in the description, is intended to mean that the element is bendable to assume forms other than its original form, and that it will remain in its new form until again bent to its original or still another form; thus being distinguished from resilient and non-deformable or unbendable.

Although I have illustrated and described particular embodiments of the invention, it will be realized by those skilled in the art that various changes may be made in the details of the construction without departing from the spirit of the invention or without exceeding the scope of the claims.

I claim:

1. An earring comprising: a support formed of a single length of deformable material and having a saddle with forwardly and rearwardly extending wings adapted to seat on the inner surfaces of the pinna of a human ear, a body-portion-saddle-bridge extending outwardly at an angle from said saddle, a body portion formed at least in part by two parallel adjacent sections of said material and extending downwardly from said body-portion-saddle-bridge and adapted to traverse the outer face of the ear lobe substantially from the bottom of the outer U to the junction between the ear lobe and the head and having a rearwardly extending adjusting loop portion, a body-portion-retainer-bridge curving generally backwardly from said body portion and adapted to fit loosely around and under the lobe of the ear, and a retainer extending backwardly and upwardly from said body-portion-retainer-bridge and adapted to fit loosely behind the lobe to maintain said saddle in its seated position; a flap having a clamp portion crimped around said adjacent sections of material of said body portion thereby to reinforce the body portion and having an ornament securing extension formed integrally with and extending from said clamp portion adjacent, but free from, said body portion.

2. An earring as described in claim 1 wherein in said flap is provided with a transverse hole for riveting or staking an ornament thereto.

3. An earring as described in claim 1 wherein in said ornament securing extension is provided with a cup-shaped surface for receiving an ornament.

4. An earring as described in claim 1 wherein in said ornament securing extension is provided with a plurality of undercut surfaces so that an ornament may be secured by the anchoring action of cement against said surfaces.

5. An earring comprising: a support having a saddle with forwardly and rearwardly extending

wings adapted to seat on the inner surface of the pinna of a human ear, a body-portion-saddle-bridge extending at an angle from said saddle, a body portion extending downwardly from said body-portion-saddle-bridge and adapted to traverse the outer face of the ear lobe, a body-portion-retainer-bridge extending arcuately from the lower end of the said body portion and adapted to fit loosely around the lobe of the ear, and a retainer extending backwardly and upwardly from said body-portion-retainer-bridge and adapted to fit loosely behind the lobe to prevent said saddle from being dislodged from its seated position during use, said support being formed principally of elongated deformable material, said portion comprising contiguous, substantially parallel elements one of which terminates in a free end adjacent said arcuate body-portion-retainer-bridge; and a flap having a clamp portion substantially enclosing said free end of said material and a contiguous section of said body portion maintaining them in frictional engagement to reinforce said body portion, and an ornament securing extension supported by and extending from said clamp portion.

6. An earring comprising: a support having a saddle with forwardly and rearwardly extending wings adapted to seat on the inner surfaces of the pinna of a human ear, a body-portion-saddle-bridge extending at an angle from said saddle, a body portion extending downwardly from said body-portion-saddle-bridge and adapted to traverse the outer face of the ear lobe and including an adjustment loop portion, said body portion comprising contiguous, substantially parallel elements one of which terminates in a free end adjacent said adjustment loop, a body-portion-retainer-bridge arcuately extending from the lower end of said body portion and adapted to fit loosely around the lobe of the ear, and a retainer extending backwardly and upwardly from said body-portion-retainer-bridge and adapted to fit loosely behind the lobe to prevent said saddle from being dislodged from its seated position during use; said support being formed of elongated material those parts being deformable which form the saddle, loop portion, body-portion-retainer-bridge and retainer; and a clamp portion substantially enclosing said free end of said material and a contiguous section of said body holding them in tight frictional engagement thereby to reinforce said body.

7. An earring comprising: a support having a saddle with forwardly and rearwardly extending wings adapted to seat on the inner surfaces of the pinna of a human ear, a body-portion-saddle-bridge extending at an angle from said saddle, a body portion extending downwardly from said body-portion-saddle-bridge and adapted to traverse the outer face of the ear lobe, said body portion comprising contiguous substantially parallel elements one of which terminates in a free end, a body-portion-retainer-bridge arcuately extending from the lower end of said body portion and adapted to fit loosely around the lobe of the ear, and a retainer extending backwardly and upwardly from said body-portion-retainer and adapted to fit loosely behind the lobe to prevent said saddle from being dislodged from its seated position; said support being formed of elongated material which is deformable in those areas from which the saddle, the body-portion-retainer-bridge, and the retainer are formed; and a flap secured to said body portion and having an ornament securing extension which is provided

with a plurality of undercut surfaces whereby an ornament may be securely and firmly anchored to said base by adhesive cement in contact with said ornament and said undercut surfaces.

8. An earring support formed of deformable elongated material and including a saddle having forwardly and rearwardly extending wing loops and adapted to engage in the concha of the pinna of an ear for supporting the weight of an ornament, a body portion supported by said saddle and adapted to carry an earring ornament, an adjustment loop formed integrally with said body portion and adapted to be bent in order to fit said support to a particular ear configuration and size, said body portion comprising contiguous, substantially parallel elements one of which terminates in a free end adjacent said adjustment loop, a retainer extending from said body portion and adapted to engage loosely behind the lobe of the pinna to prevent displacement of the earring support from the pinna during use, a clamp portion adjacent said free end of said material and holding a contiguous section of said body portion in firm engagement therewith, an ornament supporting extension supported by said clamp portion, and an ornament secured to and supported by said extension.

9. An earring support formed of deformable elongated material and including a saddle having forwardly and rearwardly extending wing loops and adapted to engage in the concha of the pinna of an ear for supporting the weight of an ornament, a body portion supported by said saddle and adapted to carry an earring ornament, an adjustment loop formed integrally with said body portion and adapted to be bent in order to fit said support to a particular ear configuration and size, said portion comprising contiguous, substantially parallel elements one of which terminates in a free end adjacent said adjustment loop, a

5

25

retainer extending from said body portion and adapted to engage loosely behind the lobe of the pinna to prevent displacement of the earring support from the pinna during use, and a clamp portion adjacent said free end of said material and holding a contiguous section of said body portion in firm engagement therewith.

10. In an earring construction, the combination of, a saddle which is adapted to rest at the bottom of the concha of an ear and comprising a continuous piece of deformable wire bent into an elongated loop with the ends of the wire positioned in side by side contiguous relationship and adapted to project outwardly along the outer U of the ear and with said loop having two portions projecting oppositely from each other and transversely of said ends of the wire, and an ornament holding and clamping means comprising a clamping portion substantially enclosing and clamping said ends of the wire, an ornament attaching portion positioned to extend downwardly along the ear lobe, and a retainer portion extending from said ornament attaching portion and adapted to extend around the lobe of the ear and between the ear and the head of the wearer.
